INVENTOR

JOHAN OLEANDER HAGBERG

by ATTORNEY

UNITED STATES PATENT OFFICE.

JOHAN OIVIND HAGBERG, OF CHRISTIANIA, NORWAY.

BUTTON.

1,367,963.

Specification of Letters Patent.

Patented Feb. 8, 1921.

Application filed April 26, 1919. Serial No. 292,964.

To all whom it may concern:

Be it known that I, JOHAN OIVIND HAGBERG, citizen of Christiania, Norway, residing at Normanns Gate 9, Christiania, Norway, have invented a new and useful Improvement in Buttons; and I do hereby declare the following to be a full, clear, and exact description of the same.

This invention relates to improvements in separable buttons of the class having a back member consisting of a disk to which is fastened a stem provided with a head, and a front member in the rear side of which there is provided an aperture adjacent which is a part having spring edges to engage and hold the head of the stem, and in which front and back members of the button are joined by forcing the stem of the back member into engagement with the spring member of the front member.

An object of this invention is the provision of new and improved means for facilitating the connection and disconnection of the front and back members of the button. For this purpose there is placed on the stem a sleeve having a diameter greater than the diameter of the head of the stem and which may be forced into the aperture of the front member, whereupon the spring engagement of the head is released and the back member and front member may be separated.

One embodiment of this invention is illustrated in the accompanying drawings in which:

Figure 1 is a sectional view of the front and back members in connected position.

Fig. 2 is a sectional view showing the sleeve in engagement with the spring member, when the front and back members are to be separated.

Fig. 3 is a sectional view of the button showing the front and back members during the separating operation.

In the drawings 1 indicates the supporting plate of the back member and 2 a stem inserted into the same. The end of the stem 2 is formed with a rounded head 3, the front of which serves as a wedge and the rear part of which is cut perpendicularly to the stem to form a shoulder. Upon the stem 2 is placed a loose sleeve 4 the diameter of which is greater than that of the head 3. The front member 5 has a springy convex part adjacent an aperture 6 therein.

The front and back members of the button are joined by forcing the stem 2 into the

aperture 6. When entering the aperture the rounded head 3 cams the edges of the spring member outwardly until the shoulder on the head is in position to be engaged by the spring when the spring will move to this position and thereby arrest the head in said aperture. In order to again separate the front and back members of the button the latter is forced toward the front member. This forces the sleeve 4, by the plate 1 contacting therewith, into the aperture 6. The sleeve 4, in entering the aperture forces the spring member until the edges thereof engage the surface of the sleeve. If the back member is now drawn rearwardly, the stem 2 slides in the sleeve 4, which at this time is held by the frictional engagement with the spring members, until the shoulder on the head 3 comes in contact with the sleeve. The continued movement of the back member draws the sleeve with it out of the aperture, the head 3 passing through the aperture 6 without the spring engaging the shoulder on the head because of the contact of the sleeve 4 with the shoulder and the greater diameter of the sleeve. The sleeve 4 is normally held out of engagement with the spring by the parts of the member 5 adjacent the aperture 6.

Buttons made according to the present invention have considerable advantage over the buttons heretofore known, since the former may be disconnected and connected again very many times without any appreciable wear.

Because of the comparatively great diameter of the sleeve 4 the wearing of the button-hole of the garment is considerably reduced.

I claim as my invention:

1. A new article of manufacture of the class described comprising a front member having a button head said front member being provided with an aperture and spring means adjacent said aperture; a back member provided with a stem and an enlarged head thereon having a shoulder adapted to enter said aperture and to be engaged by said spring means; and a sleeve mounted on said stem having a diameter greater than the diameter of the head and adapted to be inserted in said aperture to engage the spring means and to maintain the same out of range of the shoulder on the head when the front and back members are pulled apart, and said sleeve being adapted to pre-

2
vent the enlarged head from damaging the fabric to which the article of manufacture is applied when the head is withdrawn through the fabric on the removal of the but-
5 ton.

2. A button having a front member pro-
vided with an aperture and spring means ad-
jacent said aperture; a back member pro-
vided with a stem and an enlarged head
10 thereon having a shoulder adapted to enter
said aperture and to be engaged by said
spring means; and a sleeve loosely mounted
on said stem and adapted to be inserted in
said aperture by forcing inwardly said stem
15 and adapted by this movement to engage
and release the spring means, said spring
means frictionally engaging said sleeve to
hold the same until the head on said stem
during its outward movement engages the

sleeve, whereupon the head forces said sleeve 20
out of the aperture, said sleeve prevent-
ing the spring means from engaging the
shoulder on the head during the retraction
of the head and sleeve through said aper-
ture, and stopping means for normally hold-
ing said sleeve out of engagement with said
spring means, said stopping means being
adapted to yield when pressure is exerted
thereon by the sleeve in the preparatory op-
eration of disconnecting the front and back 30
members.

In testimony whereof, I have signed my
name to this specification in the presence of
two subscribing witnesses.

JOHAN OIVIND HAGBERG.
